CLAIM

The ornamental design for a cervid skull boiler, as shown and described.

DESCRIPTION

FIG. 1 is a top front perspective view of my new design for a cervid skull boiler;

FIG. 2 is another top front perspective view thereof;

FIG. 3 is a front elevation view thereof;

FIG. 4 is a side elevation view thereof; and,

FIG. 5 is a rear elevation view thereof.

The portions of the cervid skull boiler shown in broken line form no part of the claimed design.
